Primary Examiner — Darlington Ly*Assistant Examiner* — Nasim Abdulaziz Ali(74) *Attorney, Agent, or Firm* — June E. Rickey(57) **CLAIM**

The ornamental design for a tire, as shown and described.

DESCRIPTION

FIG. 1 is a front perspective view of a tire embodying my new design;

FIG. 2 is a front elevation view thereof;

FIG. 3 is a side elevation view thereof, the other side elevation view being a mirror image thereof;

FIG. 4 is an enlarged, partial front perspective view thereof; FIG. 5 is an enlarged, partial front elevation view thereof; and,

FIG. 6 is an enlarged, partial side elevation view thereof. The broken lines and the sidewall region between the broken lines that define the inner bead and the sidewall depict subject matter that forms no part of the claimed tire design and are included for the purpose of illustrating the full tire.

1 Claim, 6 Drawing Sheets(56)
